UNITED STATES PATENT OFFICE

HAROLD W. A. DIXON, OF HOLLIS, NEW YORK, ASSIGNOR TO COLUMBIA RIBBON & CARBON MANUFACTURING COMPANY, INC., OF GLEN COVE, LONG ISLAND, A CORPORATION OF NEW YORK

WRAPPING MACHINE

Application filed February 3, 1928. Serial No. 251,511.

This invention relates to an improved apparatus for wrapping articles, being particularly adapted for use in the manufacture of typewriter ribbons, in applying a wrapper 5 to the spool. Heretofore this wrapper, which is usually tin foil, has been applied by hand, and while hand operators after long practice become fairly expert in applying the wrapper to the spool, nevertheless the hand 10 process is slow as compared to machine wrapping by my apparatus. The present invention provides a machine capable of applying the wrapper automatically, the only hand operation necessary being the supplying of 15 the spools to a magazine, the machine wrapping the spools automatically and discharging them upon an unloading platform.

While the present machine will be described with reference to the wrapping of 20 spools of typewriter ribbons, it is to be understood that this use is illustrative and not definitive inasmuch as the machine is capable of wrapping other articles.

In the accompanying drawings wherein an 25 embodiment of my invention has been illustrated,

Fig. 1 is a plan view;

Fig. 2 is a section on the line 2—2 of Fig. 1;

Fig. 3 is a section on the line 3—3 of Fig. 1;

Fig. 4 is a section on the line 4—4 of Fig. 1;

Fig. 5 is a fragmentary view of certain details of the machine; while

Figs. 6, 7 and 8 are sectional views of the 35 slides employed in applying the wrapper, these figures showing the wrapper in its various stages of application.

The machine of this application, as above mentioned, is automatic in operation, it being merely necessary to charge a magazine or 40 feed hopper with the spools of ribbon, or other articles to be wrapped, the spools thereafter feeding automatically into the wrapping mechanism, one by one, where it is wrapped and thereafter discharged from the 45 machine.

In general, the machine of this application provides an apparatus in which the wrapping material such as tin foil for example is fed to the machine and cut off to the desired 50 length, automatically whereupon an article

to be wrapped is advanced to position thereon, a plunger then descending upon the spool or other article to be wrapped to depress the spool and the tin foil which is beneath it below the level of a slide which is then reciprocated across the top of the spool, one motion of the slide folding a part of the foil over the top of the spool while the reverse motion of the slide folds the remainder of the foil to complete the wrapping operation. 55 I might add at this point that inasmuch as the spool is deposited upon the foil in the first instance, depression of the spool and foil effects a wrapping of the bottom and sides of the spool, so that it only remains to fold 60 the foil over the top of the spool to complete the wrapping operation. 65

Advancing and severing mechanism for the wrapping material

70

As above pointed out the wrapping material, tin foil for example, is fed to the machine automatically, and cut off automatically to length. The foil designated 2 is fed to the machine by two feed rollers, an upper roll or roller 3 and a lower roll or roller 4. The foil which is fed from a supply roll, passes to the machine over a guide roller 5, thence between feed rollers 3 and 4 and through guide ways 6 to position directly above the 75 restricted opening or wrapping station 7, provided in the bed plate 8 of the machine, this opening which extends completely through the bed plate receives the spool in the wrapping operation, in fact effects in conjunction with other mechanism, a partial 80 wrapping, all of which will be explained fully 85 hereinafter.

Inasmuch as the entire machine is operated intermittently owing to the several steps involved in the feeding and wrapping process, the wrapping material 2 is necessarily fed or advanced only intermittently. To this end, therefore, the shaft 9 to which the lower feed roller 4 is fixed is provided with a gear 10, 90 loose on the shaft, and meshing with a rack 11. The gear 10 carries a disc 12, and mounted on the face of this disc is a pawl 13. The pawl 13 engages and cooperates with a ratchet wheel 14 rigidly attached to the 95 100

shaft 9. The rack 11 is adapted to be actuated in a direction to move the gear 10 clockwise as viewed in Fig. 4 by a bar 15 integral with the rack and mounted in guides 16, the lower end of this bar being attached as indicated at 17, to one end of foil feed lever 18. This lever is pivotally mounted at 19 and is rocked on its pivot to actuate the rack 11 by a cam 20, which I will term the foil feed cam, this cam being mounted on a drive shaft 21 which is the drive shaft for the entire machine and is driven by a motor M.

The foil feed lever 18 is provided with a cam follower 22 made adjustable so as to vary the extent of movement of the feed rack. The reverse movement of the feed rack is limited by a stop 22'.

With the cam 20 rotating clockwise as viewed in Fig. 2 it will be apparent that the resulting movement of the foil feed rack 11 will cause the gear 10 to rotate clockwise as viewed in Fig. 4, and inasmuch as the disc 12 is attached thereto, the disc will be caused to rotate in a clockwise direction also, and the pawl 13 engaging the ratchet wheel 14 will cause the latter together with the roll 4 to rotate clockwise. Consequently the foil 2 will be advanced to the right as viewed in Fig. 4, traveling through the guide 6 to a position over the opening 7 heretofore referred to in the bed plate 8. The amount of foil fed on each operation depends of course upon the amount of travel given to the foil feed rack 11 which as above mentioned, can be adjusted as desired.

The next step in the operation of my improved machine is the cutting to length of the wrapping material 2, and this is effected by a knife blade 23 mounted adjacent the end 40 of the foil guides 6 and pivoted at 23'.

The knife 23 is adapted to be actuated by knife-actuating rod 24 attached at its upper end to the knife blade opposite the pivot 23' and pivoted at its lower end to cut-off lever 45. This lever is pivoted at 19' and is provided intermediate its ends with a cam follower 26 cooperating with cut-off cam 27 mounted on the shaft 21. The cut-off cam 27 as will be seen from Fig. 2 is provided in its face with an abrupt depression 28, so that as the cam is rotated the knife 23 will drop suddenly to sever the foil. The knife is then raised to its original position by the continued rotation of the cam moving the cam follower 26 out of the depression 28.

Mechanism for advancing unwrapped articles into machine

It is desired to provide means for feeding or advancing the unwrapped articles in succession into the machine, and in this connection I provide a feed hopper or magazine 29 positioned slightly to one side of the foil and into which the articles are first loaded. This hopper or magazine is equipped with a maga-

zine slide 30 removable from the magazine. The slide is conveniently composed of a tube of fibre, preferably split lengthwise so that the same can be placed with a lateral movement over a plurality of spools and then readily slipped into the feed magazine. Additional spools are added from time to time, as necessary, without however, removing the slide from the magazine. The spools feed by gravity through the slide as will be understood. The magazine is open at the side and as the spools move downwardly through the magazine the lowermost spool comes to rest on the bottom of the magazine from which it is later projected by a pusher 33. 31 designates a folder slide which is provided with an opening 32 extending completely therethrough, and prior to the folding or wrapping operation this opening lies directly over the opening 7 already referred to in the bed plate 8. Inasmuch as the articles to be wrapped come to rest at one side of this opening 7, it is necessary that these articles be given a lateral movement to the left as viewed in Fig. 2 out of the bottom of the magazine. To effect this movement, a pusher 33 is mounted above the folder slide 31, this pusher being provided with rack teeth 34 on its upper face, engaging a gear 35 mounted on shaft 36. This shaft carries a sprocket 37 for a chain 38, this chain passing over another sprocket 39. One end of the sprocket chain leads downwardly and is attached at its lower end to spool feed lever 40. The opposite end of the chain is connected through a spring 41 with a fixed bracket 42. The spool-feed lever which is pivoted at 43 to a bracket B on the frame of the machine is provided with a cam follower 44 cooperating with spool-feed cam 45 on the shaft 21. As this cam rocks the spool feed lever 40 about its pivot, the sprocket 37 and gear 35 will be caused to rotate clockwise as viewed in Fig. 2 and the spool feed pusher 33 will be moved to the left into engagement with the lowermost article in the magazine or hopper 29, to move this article laterally, this movement continuing until the article comes to rest upon the tin foil and against a permanent magnet 33' which holds the spool in proper alignment immediately above the opening 7 in the bed plate 8 and the opening 32 in the folder slide 31 these two openings at this time being in register. After the cam follower 44 rides off the high spot on the cam 45 the pusher will be retracted to its initial position by spring 41, as will be obvious.

Initial wrapping operation

The spool or other article to be wrapped having been moved into proper position on the foil, means are next brought into operation for forcing the spool, with the foil beneath it downwardly through the restricted

opening 32 in the folder slide 31 and into the similarly restricted opening 7 in the bed plate 8. The mechanism comprises a plunger 46 acting in opposition to a coil spring 47 which surrounds its stem. The plunger is positioned at all times immediately above the opening 7. The upper end of the plunger stem is bent laterally and then downwardly as indicated at 48 in Fig. 3, and is guided 10 against any motion of rotation by guide 49.

The lower end of the plunger stem is pivotally attached to the inner end of a plunger actuating lever 50, see Fig. 2. This lever carries a cam follower 51 cooperating with 15 plunger cam 52 mounted on the shaft 21 and as this cam rotates the lever 50 will be rocked in the proper direction to move the plunger 46 downwardly into contact with the previously advanced spool and which I will designate 20 53, forcing the same, together with the foil, downwardly through the opening 32 in the slide 31 and into the recess 7 in the bed plate. Inasmuch as the opening 32 in the folder slide is of smaller dimensions than the 25 tin foil and inasmuch as the opening 7 is likewise restricted, it will be apparent that the bottom and sides of the spool will have now been wrapped or covered, the excess foil designated 54 projecting above the top of 30 the spool as illustrated in Fig. 4. The spool 53 while it has been pushed or projected into the opening 7, is not permitted to pass entirely therethrough but is gripped by a holding spring 55 located in a groove provided for 35 that purpose about the opening. This spring is covered with felt, plush or other suitable material 55' which prevents tearing the foil.

Completion of the wrapping operation

40 The projecting material 54 is folded over the top of the spool by the folder slide 31, and the mechanism for effecting this operation will now be described.

The folder slide 31 is attached to folder-slide lever 56 through a connecting member 57 adapted to reciprocate in an opening 58 provided for that purpose in the bed plate 8 as will be seen from Fig. 2. This lever which is pivoted intermediate its ends has its 45 lower end provided with an adjustable cam follower 59 cooperating with folder slide cam 60 mounted on the shaft 21. The rotation of the cam 60 will rock the folder slide lever 56 about its pivot in a direction to move 50 the folder slide 31 to the left from the position indicated in Fig. 2 into the position indicated in Fig. 6, the edge of the opening 32 as the slide passes over the spool folding a portion of the foil 54 downwardly over the 55 top of the spool 53 as will be understood. As the cam follower 59 moves off the high spot of the cam 60, the slide lever 56 will be caused to move in the opposite direction under the action of the spring 61, the cam 60 being so shaped that this spring will move

the folder slide from the position indicated in Fig. 6 to the position indicated in Fig. 7. As illustrated in the figure the folder slide in moving to its new position, i. e., from the position of Fig. 6 to that of Fig. 7, will fold the remainder of the foil over the top of the spool. I have designated this portion of the foil 54'. The spool or other article 53 is now completely covered, the foil having been placed about the same so as to embrace the entire article, and the folder slide returns to position to bring the opening 32 therein into register with the opening 7 in the bed plate, ready for the next spool.

Discharging mechanism

On the next cycle of operation of the apparatus thus far described, a second article is fed to position above the restricted opening 7, as will be understood and as the plunger 46 descends to force this second spool into opening 7, it will displace the previously covered spool and the latter will drop to the bottom of the bed plate, lying in the opening 62 therein and resting upon an unloader slide 63 which prevents the spool from dropping entirely out of the plate. In the final operation of wrapping the second spool, however, the folder slide 31 is moved to the right as shown in Fig. 7, this movement of the folder slide moving the unloader slide 63 in the same direction, the two slides being united by the member 57. The extreme movement of the unloader slide 63 completely uncovers the opening 7, so that 80 the first wrapped spool is now free to fall out of the machine and into the unloading chute 64. The unloading chute is inclined and the wrapped article will slide or roll down the same finally to be brought to rest at the discharge end thereof by stop member 65. This member is in the form of a lever pivoted at 85 66 and carrying at its outer end, a curved member 67 curved to the general shape of the spool and extending laterally with respect to the lever. This will appear from an inspection of Fig. 5. The article as it discharges from the end of the discharge chute 64 to be stopped by member 65 falls upon an unloading platform 68. This platform is provided with a series of grooves 69, 70 and 71 on its upper face, and means are provided whereby the platform will be moved at the proper time to bring a groove at the end of the discharge chute. The purpose of the unloading platform is to enable a number of spools to be deposited thereon and arranged in a tier or row adapted to be readily removed for packing. In the position of the unloading platform as illustrated in Fig. 3, 90 the rear groove 69 is adjacent the end of the discharge chute. In order that the spools as they are deposited on the platform may be moved laterally to make room for the next spool, I provide a plunger 72 adapted to be

95 moved laterally to make room for the next spool, I provide a plunger 72 adapted to be 100 moved laterally to make room for the next spool, I provide a plunger 72 adapted to be 105 moved laterally to make room for the next spool, I provide a plunger 72 adapted to be 110 moved laterally to make room for the next spool, I provide a plunger 72 adapted to be 115 moved laterally to make room for the next spool, I provide a plunger 72 adapted to be 120 moved laterally to make room for the next spool, I provide a plunger 72 adapted to be 125 moved laterally to make room for the next spool, I provide a plunger 72 adapted to be 130

actuated by a pin 73 carried by a lever 74 connected through a leverage system comprising levers 74' and 74'' to a rod 75, which is provided at one end with an arm 76 adapted to engage the plunger 72. When the rod 75 is rocked through pin 73, levers 74, 74' and 74'' by depression of the lever 50 already referred to, the plunger 72 is moved to the left into engagement with a spool in the groove 69 in the unloading platform forcing the same to the left. The row of spools is backed by a weight 77' to keep them on edge and accessible for easy removal. Obviously, therefore, the spools will be fed laterally intermittently as they are discharged upon the unloading platform until a groove is filled, that is, until there is a row of spools in said groove extending practically entirely across the unloading platform.

As above stated, however, the unloading platform contains several of these grooves for the reception of the wrapped spools and initially the platform is moved to the left as viewed in Fig. 3 until the groove 71 lies adjacent the unloading chute. Of course this groove is loaded as just described in connection with the groove 69. After this groove has been fully loaded, however, it becomes necessary to move the unloading platform to the right until the next groove, to wit, the groove 70 comes abreast of the discharge end of the unloading chute. This is done automatically. The mechanism for effecting this operation is shown in Figs. 1, 2 and 3. Referring to these figures it will be seen that a slide 77 which I will call the unloading platform slide extends transversely of the machine and is provided on each side with a series of lugs, the lugs at one side being designated 80 while those on the other side are designated 81. These lugs which I will term controlling lugs are provided for controlling the movement of the slide 77 and are spaced to correspond to the spacing of the grooves 69, 70 and 71 in the unloading platform. The slide 77 is attached to the unloading platform and to its underside a weight 82 is attached by a cable 83 running over a pulley 84. The tendency of this weight is to feed or draw the slide 77 downwardly as viewed in Fig. 1, or to the right as viewed in Fig. 3, carrying with it the unloading platform. Cooperating with the stops 80 is a movable stop or pawl 85 while cooperating with the stops 81 is a pawl 86. The pawl 85 is connected by a pin and slot connection to a movable plate 87. The pawl 86 is fixed to this plate. Lying beneath the slide 77 as viewed in Fig. 1, and attached to the plate 87 is a pin 88 adapted to cooperate with a cam 89. This cam is driven from worm and gear 90 off the main drive shaft 21 and as the cam is rotated into engagement with the pin, the latter is caused to move to the right as viewed in Fig. 1, and as the pin rides off the cam, the plate 87 will

be moved to the left under the action of the spring 87'. Assuming that the unloading platform slide 77 is in its initial position, to bring the groove 71 in the unloading platform adjacent the discharge end of the unloading chute and assuming that this groove has been filled, movement of the plate 87 to the right under the action of the cam 89 will move the pawl 86 from engagement with one of the stops 81, while the pawl 85 will have moved beneath or in the path of a stop 80 on the opposite side of the slide 79 so that with the pin 88 on the high spot of the cam 89 the slide 77 is still held stationary. As the pin 88 rides off the cam 89, however, the plate 87 is moved to the left as viewed in Fig. 1 under the action of the spring 87' to withdraw the pawl 85 from engagement with its stop 80. The stops 80 and 81 are offset slightly so that when the pawl 85 is in engagement with a stop 80, the pawl 86 is out of engagement with a corresponding stop 81. Consequently neither of the pawls 85 and 86 is at this instance in engagement with a stop and the slide 77 is free to be moved under the action of the weight 82 to the right as viewed in Fig. 3 and will continue this movement until the groove 70 in the unloading platform moves adjacent the discharge end of the unloading chute whereupon the pawl 86 will engage a stop 81 and further movement of the slide 77 will cease.

Obviously when the groove 70 becomes filled the unloading platform will be again advanced to bring the groove 69 into proper position with respect to the unloading chute.

It is obvious from the foregoing that I have provided a machine capable of wrapping articles such as spools of typewriter ribbons for example, which is automatic in its operation, the articles after being charged into a magazine being handled thereafter automatically throughout the wrapping of the articles and their discharge from the machine.

It is evident that various modifications may be made in the construction above described within the purview of this invention.

What I claim is:—

1. In a machine provided with a wrapping station at which articles are wrapped, means for moving an article to be wrapped together with a wrapper therefor into said wrapping station, the restricted opening provided by the wrapping station effecting on this movement a partial wrapping of the article, resilient means adjacent the wrapping station for retaining the wrapper and partially wrapped article therein, a member for completing the wrapping operation, and means for feeding a second article and wrapper into said station to partially wrap the second article and to simultaneously discharge the wrapped article.

2. In a machine for wrapping articles, the

combination of a folder slide and an unloading slide, said slides being arranged in spaced parallel relation, means for effecting the simultaneous reciprocation of said slides, a 5 plate between said slides and provided with an opening for the reception of articles to be wrapped, the folder slide being provided with an opening through which wrappers and articles to be wrapped are fed to the opening 10 in said plate, the reciprocation of said folder slide completing by reason of said opening the application of a wrapper to the article to be wrapped, the end of said unloading slide overlapping the opening in the folder slide 15 to prevent discharge of a wrapped article from the opening in the intermediate plate simultaneous with the movement of a second article into said opening.

3. In a machine provided with a wrapping 20 station at which articles are wrapped, means for feeding wrapping material to said station and cutting the material to length, a magazine for the articles to be wrapped positioned at one side of the wrapping station, a 25 plunger for effecting discharge of articles singly from said magazine and lateral movement of the articles to and upon the wrapper at the wrapping station, a plunger movable transversely with respect to the movement 30 of the first mentioned plunger to move an article to be wrapped and a wrapper therefor into the wrapping station, this movement effecting partial wrapping of the article, a folder slide movable in timed relation with 35 said plunger for completing the wrapping operation, and an unloading slide attached to the folder slide for controlling the discharge of a wrapped article from the wrapping station.

40 4. In a machine for wrapping articles the combination of a magazine for articles to be wrapped, means for placing wrappers for the articles to be wrapped at a wrapping station with which the machine is provided, a plunger 45 for laterally moving articles from said magazine to and upon a wrapper at the wrapping station, a plunger for depressing a wrapper and article to be wrapped into said wrapping station to partially wrap the article, a 50 folder slide, operable thereafter to complete the wrapping operation, an unloading slide adapted to prevent movement of the article until operation of the folder slide and consequent completion of the wrapping operation, means for moving said unloading slide 55 to an operative position, means for moving the succeeding article to be wrapped into operative position relative to said plunger the operation of which effects a partial wrapping 60 of the succeeding article and simultaneously the discharge of the preceding completely wrapped article, a discharge chute the receiving end of which is adjacent the wrapping station for receiving the wrapped articles, a 65 landing platform at the discharge end of the

chute for receiving articles from the chute, and means for bringing the articles to rest upon the landing platform.

5. In a machine for wrapping articles, the 70 combination of a plate provided with a restricted opening and providing a wrapping station, means for positioning a wrapper over said opening, means for feeding an article to be wrapped into superposed relation to said wrapper, and a magnet for retaining the unwrapped article in such position.

6. In a wrapping machine the combination of a wrapping station comprising mechanism for wrapping an article, means for moving an article to be wrapped and a wrapper 80 therefor into the wrapping station partially to wrap said article and to engage the immediately preceding article, which is completely wrapped, the engagement of the two articles effecting discharge of the completely wrapped 85 article from the wrapping station upon an unloading slide, and means for actuating the unloading slide to remove the wrapped article therefrom.

This specification signed this 31st day of 90 January, 1928.

HAROLD W. A. DIXON.
